CLAIM

The ornamental design for a document tray, as shown and described.

DESCRIPTION

This application claims the benefit of the filing date of U.S. application Ser. No. 12/749,905, filed Mar. 30, 2010, the entire disclosure of which is expressly incorporated by reference herein.

FIG. 1 is a perspective view of a document tray showing the new design;

FIG. 2 is a front elevational view of the document tray shown in FIG. 1;

FIG. 3 is a rear elevational view of the document shown in FIG. 1;

FIG. 4 is a right side elevational view of the document tray shown in FIG. 1;

FIG. 5 is a left side elevational view of the document tray shown in FIG. 1;

FIG. 6 is a top view of the document tray shown in FIG. 1; and,

FIG. 7 is a bottom view of the document tray shown in FIG. 1.
